UNITED STATES PATENT OFFICE.

JOHN T. FAGAN, OF CLEVELAND HEIGHTS, OHIO.

ROCKER ARM.

Application filed May 28, 1926. Serial No. 112,262.

This invention relates to rocker arms, such for example as are used to operate the valves known as the "overhead type" of an internal combustion engine.

An object of the invention is to provide a rocker arm that is quiet in operation;

10 A further object is to provide a rocker arm that has a practically frictionless bearing, and on which bearing there is practically no movement of the arm;

A further object is to provide a rocker arm in which the wearing parts are made replaceable and of a superior quality of hardened steel;

15 A further object is to provide a rocker arm that may be readily detached from the shaft for repairs when necessary without dismantling a number of parts auxiliary thereto;

A further object is to provide a simplified 20 shaft for use in connection with rocker arms;

A further object is to construct the shaft so that a rocker arm may be readily attached thereto and detached therefrom;

25 A further object is to provide a simplified shaft which supports a detachable bearing edge;

A further object is to provide a sectional shaft from which one section may be removed without disturbing the remainder of 30 the shaft;

Other objects will appear upon reading the specification.

In the accompanying drawings,

35 Figures 1, 2, 3, 4 and 5 are side, top, bottom, and left and right end views, respectively, of one form of a rocker arm.

40 Fig. 6 is a side view, partly in section, of a modified form but showing also a section of a shaft with its spring seating conical recess and bearing edge, and the grooved bearing plate, also the spring and the end of a pin or screw which centers and retains the upper end of the spring;

45 Figs. 7, 8, and 9 are bottom, and left and right end views respectively, of Fig. 6;

Fig. 10 is a view on the line 10—10 of Fig. 1, showing the bearing plate support, and half-round groove therein;

50 Figs. 11 and 12 are side and top views respectively in elevation, of a modification in which the arm is made of stampings;

Fig. 13 is a view of a longitudinal section on the line 13—13 of Fig. 12;

55 Fig. 14 is a view of a vertical section on the line 14—14 of Fig. 11;

Fig. 15 is a view of a horizontal section on the line 15—15 of Fig. 11;

Fig. 16 is a plan view, looking at the right hand end of Fig. 11;

Fig. 17 illustrates side, top and end views 60 of the grooved bearing plate;

Fig. 18 is an edge view of a detachable hardened steel contact shoe, shown in place in Figs. 11, 12 and 13;

Figure 19 illustrates top and side views of 65 a metal threaded nut 23, shown in section in Fig. 13, and which provides for the adjustment of the threaded bolt 8 so that the valves may be given the proper timing, and co-operates with the upper lock to secure the bolt 70 in adjustment;

Figs. 20 and 21 are side and top plan views 75 of an upper stamping, such as shown in Figs. 11, 12, and 13, but having the spring retaining pin stamped from the metal;

Fig. 22 is a top plan view of a metal strip, to be bent into a shaft, having portions pressed up to form cone-shaped cups for the springs upon the completion of the shaft;

Fig. 23 is a transverse section on the line 80 23—23 of Fig. 22;

Figs. 24, and 25 are sectional views showing the stages of bending and pressing to complete the shaft, Fig. 25 being a section on the line 25—25 of Fig. 28;

Fig. 26 is also a sectional view on the line 85 25—25, of Fig. 28, also showing the bearing edge in place, and also showing in elevation the ends of a bolt;

Figs. 27 and 28 are side and top plan views, 90 respectively, of the completed shaft;

Fig. 29 is a view in perspective of a further modified shaft, in which strips of steel are suitably milled and drilled, and clamped and bolted together, with the bearing edge held between the metal strips;

Fig. 30 is a view of a vertical section on the line 30—30 of Fig. 29;

Fig. 31 is a view of a vertical section on the line 31—31 of Fig. 29, showing the cone-shaped recess, and the bearing edge.

Fig. 32 is a perspective view of a detached bearing edge;

Fig. 33 is a perspective sectional view on the line 33—33 of Fig. 37, showing how the 105 end of the shaft is secured to a support;

Fig. 34 is a perspective view partly in section showing one type, for example a forging, of a completely assembled rocker arm mounted on the shaft;

Figs. 35 and 36 are top and end plan views, respectively, of a sectional shaft such as shown in Fig. 29; Fig. 35 showing one of the clamps and bolt removed, and showing the joint between two sections of the shaft; 5

Fig. 37 is a side view, partly in elevation and partly in section, of the mounted shaft; and

Fig. 38 is a sectional view on the line 10 38-38 of Fig. 37.

In the modification shown in Figs. 1 to 10 inclusive, a die casting 1, made preferably of aluminum and provided with ample stiffening webs 2, has an opening 3 through 15 which passes a shaft 4, Fig. 6, upon which the rocker arm is mounted. The casting in Fig. 1 is provided with a detachable shoe, 5, at the right end, made of hardened steel, and is provided with an enlargement 6 at 20 the left end through which is drilled a hole 7, Fig. 3, for a bolt 8, Fig. 6. The casting is further provided with an especially shaped base 9 in the opening 3 for holding a bearing plate 10, Fig. 6. In Figs. 1 and 2, an upper hole 11 is provided through which passes a 25 screw or pin, now shown, to engage the upper end of a spring 12, Fig. 6, a pin 16 being shown in Fig. 6.

In Fig. 6, at the right is shown a 30 removable bolt 13, the face 14 of which is hardened, and which takes the place of the shoe 5 in Fig. 1. At the left of Fig. 6 is the bolt 8, having the hemispherical head 15 made of hardened steel. At the top of the 35 opening is a pin 16, referred to above, which retains and centers the upper end of the spring 12, the lower end of which is seated in the cup 17 of the shaft 4. Securely held in the shaft 4, is a hardened steel-bearing 40 edge 18, one form of which is shown in Fig. 32, and which is provided with a lower rounded edge comparable to a half of a round steel rod of small diameter, the bearing edge resting in the hardened steel bearing block 10, see also Fig. 17, there being a 45 very small, practically no movement, of the bearing 10 at the point of support during use. The small contact surface of the rounded edge of the bearing on the block 50 provides a substantially frictionless bearing, substantially free from wear, and is also noiseless. The bearing corresponds to a roller bearing. The hemispherical surface 15, on the bolt 8, rests in any type of hemispherical recess in the top of a push rod, not shown.

In the modification shown in Figs. 11 to 16, the rocker arm is made of metal stampings, or of thin metal forgings. The stamping 20 is of thin sheet metal, provided with lateral sockets or supports 21 to receive the bearing plate 22, Fig. 13. At the left end is an enlargement to receive the threaded block 23, Figs. 13, 15, and 19, through which 60 passes the bolt 8. At the right end, a de-

tachable hardened contact shoe, 24, Figs. 11, 13, and 18, is detachably secured. The bolt 8 securely holds in place the upper overhanging arm 25, Figs. 11, 12, 13, 20, and 21, which is also a metal stamping or 70 thin forging, and which is provided with stiffening walls 26, which engage the sides of the stamping 20 at one end.

The free extremity of the arm 25 is provided with a spring retaining pin or rivet, 27, Fig. 13, or may have a tongue of metal pressed downwards, as at 28, Figs. 20 and 21. The shaft 4, with its bearing edge and spring, shown in Fig. 13, is assembled as in Fig. 6. The completely assembled rocker arm shown 80 in Figs. 11, 12, and 13 may be applied to the shaft while the shaft is in place, and is substantially balanced on each side of the bearing edge.

Illustrations in Figs. 22 to 28 show a 85 modified shaft made of a metal stamping or forging. In Fig. 22, a metal strip 30, punched for bolt holes 31, and additional holes 32, with punched-up flaring sides, 33, Figs. 22 and 23, at properly located intervals, is stamped or forged through the stages represented by Figs. 24 and 25; Fig. 25 representing a completed shaft on the cross section 25-25 of Fig. 28. As a result of stamping or forging with proper tools, the sides 33-33 are flared outwards, forming the spring-holding cup of the shaft. The stamping or forging of the strip 30 is conducted so that the holes 31 register to receive the bolt 34, Fig. 26, and the flat undeformed sides 35 of the sheet 30 form the parallel sides 36 of the completed shaft, the opening 37 between the sides 36 receiving the bearing edge 38, also shown in Fig. 32. The bolt holes 31 are located so as to register 100 with the hole 39 in bearing edge 38, Fig. 32.

In Figs. 29 to 38 are shown views of a further modification in which the component parts comprise parallel strips of steel, 40, suitably milled to form recesses 41 on each side, Figs. 29 and 31, and drilled to receive bolts 42, Figs. 29 and 30. The strips 40-40 are further milled, or drilled after assembly, as at 45, Fig. 35, to receive the bolts 43, Figs. 29 and 33, which aid in maintaining the strips 40-40 properly spaced. Upon assembly, the spaced strips 40-40 receive the bearing edge 38, Fig. 32, the bolt 42 passing through the hole 39; the cuts 45 in the bearing edge 38 cooperating with the milled recesses 41, 110 Figs. 29 and 31, to form the spring-holding cup 46, Figs. 29, 31, 34, 35, and 38. The upper and lower edges of the strips 40 are further clamped by clamps 47, 47, Figs. 29, 115 31, 33, 35 and 37, the clamps 47-47 being drilled to receive the bolt 43, which bolts 120 may enter a threaded hole in the engine at 48, or may be secured in posts 49-49, Fig. 37, thereby being rigidly supported. The shaft in Fig. 35 is shown in sections as at 130

51, 51, 51, 51, the four ends of the strip 40 being clamped by the clamps 47, one of which is shown in dotted lines around the joined ends at 51. This construction provides for the removal of any section of the shaft without dismantling it entirely, for its repair, or removal, the dismantling being effected by the removal of the bolts 43, 43, shown in Fig. 37, and the removal of the upper clamps 47, 47.

The assembled rocker arm shown in Figs. 1 to 9 is slipped over the shaft, the bearing plate 10 pressed against the bearing edge 18, and the spring 12 placed in the cup 17 and centered around the pin 16; the shaft is then secured in its place in the engine.

With the type of rocker arm shown in Figs. 11 to 16, the rocker arm comprises a forked construction when completely assembled, and the shaft is secured in place by straddling the forked members over the shaft, and the spring placed in the cup and around the pin 27.

In operation, the valve stem 55, Fig. 34, is struck by the shoe 24 and actuated, the rocker arm receiving its motion from the engine by the ordinary operating rod, not shown, which strikes the ball-shaped head 15 of the bolt 8. In normal operation, the actual movement at the point of support between the bearing edge 38 and bearing plate 22, Figs. 13 and 34, and in Fig. 6 at 18 and 10, is an oscillating or rolling movement and is so slight as to be negligible; substantially no signs of wear appeared after a test corresponding to over thirty thousand miles of travel of an automobile. The operation of the arm is also noiseless. At the end of the test above noted, substantially no wear was observed on the surfaces 5, or 14, or 24, or the bolt head 15.

I claim:

1. A rocker arm for internal combustion engines, comprising an arm, a bearing plate, said bearing plate supported in said arm, an open-forked arm including a spring retaining means, and removable wear-resisting impact surfaces on opposite ends of said rocker arm.

2. A rocker arm comprising a metal stamping, bearing-supports secured in said stamping, an open forked arm extending over and spaced above said bearing-supports, a spring centering agent in said arm, and the extremities of said metal stamping constructed to receive wear-resisting impact surfaces.

3. A rocker arm comprising a metal stamping, bearing-supports secured in said stamping, an open forked overhanging arm spaced above said bearing-supports, a bearing in said supports, a spring centering agent in said arm and located over the bearing, and wear-resisting impact surfaces detachably secured to said metal stamping.

4. A rocker arm comprising a metal stamping, bearing-supports secured in said stamping, a separate stamping comprising an overhanging arm spaced above said bearing supports and provided with means to engage the rocker arm stamping, a spring centering agent in said arm and located above the bearing-supports, and means to hold detachable wear-resisting surfaces on said rocker arm stamping.

5. In combination, a rocker arm comprising an open forked assembly of arms constructed to straddle a shaft, a shaft located between said forked arms, said shaft provided with a spring seating means, a spring centering agent on one of said arms, a bearing-support on one of said arms, a bearing surface in said support, and a bearing on said shaft cooperating with said bearing surface, a spring cooperating with said shaft and one of said arms to retain the shaft bearing in firm but oscillatable relation with said bearing surface and thereby support said rocker arm upon said shaft.

6. A shaft comprising parallel sides, said sides spaced to receive a detachable bearing edge, cooperating spring retaining recesses on the surface opposite to the bearing edge surface, and said sides provided with means to retain the same in cooperative registry with the bearing edge.

7. A shaft comprising parallel strips, said strips spaced to receive a detachable bearing edge, each of said strips containing a recess, the recesses on the two strips cooperating to form a spring holding cup, a detachable bearing edge, said bearing edge constructed to fit between the strips and a portion thereof to form the bottom edge of said spring holding cup, means to retain said bearing edge in place, means to securely maintain the two strips in register, and means to secure the shaft to a support.

8. A shaft comprising parallel strips, said strips provided with recesses on their inner faces, said recesses located to cooperate and form a spring holding cup, a detachable bearing edge, a part of said edge constructed to form the bottom of said cup, and provided with a bolt hole, each of said strips provided with a bolt hole and located to register with each other and with the hole in the bearing edge, a bolt to clamp said strips and bearing edge together, clamp arranged to engage the strips near their ends and constructed to receive a bolt, said second bolt located to secure said shaft to a support.

9. In combination with a rocker arm, a detachable rigidly supported bearing edge comprising a thin plate and provided with a rounded edge, a bearing surface, said bearing surface arranged to roll over said edge during its movement.

10. A rocker arm comprising a trough-

like body, a curved transverse surface on the lower part of and inside of said trough, and an opening through one end of said body.

11. A rocker arm comprising a trough-like body, lateral supports within said trough, and side walls extending above the supports.

12. A rocker arm comprising a trough-like body, a passage at one end of said body, lateral supports extending in the walls of said body, said walls extending above said lateral supports.

13. A rocker arm comprising a trough-like body, a depressed intermediate portion in said trough, lateral supports extending in the walls of said body, said walls extending above said lateral supports.

14. A rocker arm comprising a trough-like body, a passage at one end of said body, a depressed intermediate portion in said trough, lateral supports extending in the walls of said body, said walls extending above the level of said lateral supports.

15. A rocker arm comprising a trough-like body, a passage at one end of said body, a curved depressed portion inside of and on the lower part of said body, upwardly extending walls from said depressed portion, and a detachable hardened wearing surface on said body.

16. A rocker arm comprising a trough-like body, a passage at one end of said body, a curved depressed portion inside of and on the lower part of said body, upwardly extending walls from said depressed portion, lateral supports in said walls, and a detachable hardened wearing surface on said body.

17. The combination comprising a trough-like rocker arm body, lateral extensions in the walls of said body, a shaft having a

section extending into the trough between the walls and into the lateral extensions, said shaft section having a rounded bearing surface on its lower edge.

18. The combination comprising a trough-like rocker arm body, a curved depressed portion inside of and on the lower part of said body, upwardly extending walls from said depressed portion, lateral extensions in said walls, a shaft having a section depending into said lateral extensions, said shaft section having a lower rounded bearing surface.

19. A rocker arm comprising a trough-like metal stamping, and a threaded block rigidly engaged by said stamping.

20. A rocker arm comprising a trough-like metal stamping, a threaded block in said stamping, and portions of the walls of said stamping folded into positive engagement with said block and securely holding the same.

21. A rocker arm comprising a trough-like metal stamping, a threaded block rigidly engaged by said stamping, a hardened detachable wearing element engaged by said threaded block, and a lock-nut-agent co-operating with said threaded block to firmly hold said detachable wearing element.

22. The combination comprising a trough-like metal rocker arm stamping, a threaded passage at one end of said stamping, a depressed intermediate portion in said stamping, lateral portions in said stamping, side walls extending above the lateral portions, and a shaft having a section depending into said lateral portions, said shaft section having a lower rounded bearing surface.

In testimony whereof I hereby affix my signature.

JOHN T. FAGAN.
